UNITED STATES PATENT OFFICE

NEAL D. HOWARD, OF MERRICK, NEW YORK

SAVINGS BANK

Application filed February 18, 1931. Serial No. 516,801.

This invention relates to a savings bank of a novel character in which deposits of coins are to be made at regular intervals, as daily, during certain periods, for example, 5 weeks or months.

One object of the invention is to provide such a bank with a series of containers mounted detachably upon a backing, each container being for use during a certain 10 period, as a week, month, or the like, and being adapted to be removed at the end of such period for deposit at a bank or similar institution, the series of containers being so arranged that upon removal of one, at the 15 end of its period of use, the proper one for the next period will be presented next in order.

Another object of the invention is to provide a means for indicating the deposit of a 20 coin for a given date, making it possible to determine at a glance whether such a deposit has been made for a particular date, or when the last deposit has been made.

A further object of the invention is to provide novel means for supporting the container in order to allow coins to be inserted into it easily and to cause the wall of the 25 container to present a firm surface through which the coins are to be pressed.

30 In the accompanying drawings:

Figure 1 is a view in elevation of the front of the entire article ready for use, showing a form intended for use during periods of one month.

35 Figure 2 is a vertical sectional side view on line 2—2 of Figure 1.

Figure 3 is a rear view of the front wall of a monthly type container, such as is shown in Figure 1.

40 Figure 4 is a front elevation of the supporting member for the front wall of the monthly type container.

Figure 5 is a view in elevation of a modified form of container intended for use during 45 a period of one week.

Figure 6 is a front view of the supporting member for use with the weekly form of container shown in Figure 5.

Figure 7 is a vertical sectional view of the 50 plate shown in Figure 6.

Figures 8, 9, 10 and 11 are details showing various modifications of the coin-receiving aperture in the container, which may be provided if desired.

In the form shown in Figures 1 to 4 inclusive, the calendar bank consists of a backing member 1, which may be of any suitable material and of a size and shape to support a plurality of calendar envelopes 2, and to allow a space 3 above the envelopes 2, and 55 preferably a space 4 below them. These spaces 3 and 4 may bear, as at 5, the name of the institution furnishing the banks or advertising matter, and may be decorated in any manner desired. The backing member 60 1 is provided with a means for hanging it, 65 as the cord 6.

Near the top of the backing member 1 are 70 projecting bolts 7 carrying clamping thumb nuts 8. These bolts 7 and nuts 8 are for the purpose of securing the envelopes 2 to the back mounting 1 and allowing their removal singly.

The envelopes 2 are preferably of standard design, having a flap, as at 10, suitable 75 for sealing, and may be of any suitable material, such as cloth or paper.

At the top of each envelope 2, open-ended 80 slots 11 are provided, the slots being spaced to engage with the bolts 7 of the mounting member 1 and hook-shaped so as to provide an offset portion 12 at their lower ends, into which the bolts are seated by moving the envelopes 2 to the left. This structure 85 makes it possible to remove each envelope from the bolts 7 without entirely removing the nuts 8 from the bolt 7. As shown in Figure 3 the slots 11 are formed while the flap is folded over, thus being duplicated in the flap and body of the envelope. The envelope may therefore be secured to the 90 backing member 1, while the flap is closed.

On the front of each envelope is printed a calendar for the period during which the 95 particular envelope is designed to be used. Thus in Figure 1 the envelope is shown bearing the calendar for the month of February, 1931, and is intended for use during that month. The others are obviously for the succeeding months of a calendar year. 100

Associated with each unit of the calendar in each of the envelopes 2 are openings 13 cut in the envelopes. These openings 13 are of suitable size and shape to permit the passage of coins into the interior of the envelope.

5 In Figure 1 these openings are shown as being rectangular and horizontally disposed beneath the units of the calendar.

They may, however, be of any desired shape and disposed in any desired relation 10 to the units. Thus Figures 8 and 9 show modifications. In Figure 8 the openings 13a are shown as having arcuate sides and being disposed horizontally below the units, while in Figure 9 the openings 13b are shown 15 as being rectangular in shape and vertically disposed to the left sides of the calendar units.

The envelopes 2 are of sufficient size, and 20 the calendars and openings 13 are so placed upon them that there is a space in the envelope below the calendars and openings sufficient to receive and hold the coins deposited. This is shown at 25 in Figure 2, in which 25 the coin 26 is illustrated as being held below the lowest opening 13d of the envelope 2.

A sheet 14 of thin material, such as tissue paper, which may be white or colored, is secured to the inside of the calendar-bearing 30 wall of the envelope. The purpose of the sheet 14 is to close the openings 13 so that a coin passed through one of the said openings will rupture the portion of the sheet 14, closing that opening, and this rupture or 35 tear in the sheet 14 at any particular opening 13 will indicate that a coin has been deposited on or for the date represented by the calendar unit adjacent that opening.

A structure more inexpensive than the 40 openings 13 and backing sheet 14 may be provided, as shown by the modified form in Figures 10 and 11. Instead of providing openings 13 in the envelope 2 and a thin backing sheet 14 as in Figures 1, 2, 3, 5, 8 and 9, the envelope may have portions 15 weakened 45 as by scoring or perforating, as shown in Figures 10 and 11. These weakened portions 15 are associated with the calendar units and may be disposed in any suitable relation 50 thereto. Thus in Figure 10 the weakened portions are shown as being horizontally disposed beneath the calendar units, and in Figure 11 as being vertically disposed to the left thereof. When this form is used, the 55 weakened portions 15 of the envelope 2 are torn by the passage of a coin into the envelope, and these tears serve to indicate the deposits in a manner similar to the tears in the backing sheet 14 already described.

60 Means are provided for holding the walls 18 and 19 of the envelopes separated and thus allow coins to be inserted through the wall 18 into the envelopes 2 more easily than if the envelope is flat. These means comprise a bowed metal plate 16, in size a little

smaller than the envelope 2 with which it is to be used in order that it may be easily slipped into the interior of the same. The plate 16 is provided with openings 17 so spaced as to register with or underly the openings 13 of the envelopes 2. Figure 4 70 shows the plate 16 having openings 17, designed to be used with the monthly form of calendar envelopes 2.

The curved metal plate 16 is provided at 75 the top with slots 20 which are shaped and spaced similarly to the slots 11 of the envelopes 2, thus permitting the plate 16, when positioned within an envelope, to be attached to the backing member 1 and supported by the bolts 7. The plate 16 holds the calendar 80 wall 18 of the envelope 2 bulged outwardly from the other wall 19, providing a space within the envelope into which the coins may be pressed, and also providing a firm support around the openings 13 so that the pressure necessary to accomplish the tearing of sheet 14 or of the weakened portion 15, may be applied without flattening the envelope.

When in use, the back mounting, bearing 90 a series of envelopes, is hung in a suitable position. The metal plate 16 is inserted into the outside or first envelope. Thus assuming that it is February, 1931, the plate 16 is inserted in the envelope for that month, and plate and envelope are attached to the backing member 1 by engaging the bolts 7 in the slots of the envelope 2 and plate 16, and moving plate and envelope to the left to seat the bolts 7 in the offset portions of the slots. The thumb nuts 8 are then tightened and the bank 95 is ready for use. If a coin is then pressed through the opening 13 associated with the first unit of the calendar, rupturing the backing sheet 14 or the weakened portion 15, it 100 will drop to the bottom of the envelope, and the tear will indicate that a deposit has been made for that date. At the end of the period for which the envelope is intended to be used, the nuts 8 are loosened and the envelope together with the plate 16 moved to the right 105 and lowered, thus removing it from the backing member 1. The plate 16 is removed from the envelope and the envelope may then be rolled, with the calendar face inward, from the bottom toward the top, and the gummed flap of the envelope used to hold the rolled envelope, containing the money on the inside, in a rolled form, thereby preventing the money from falling out. So sealed the 110 envelope may then be sent or taken to the bank for deposit. The next envelope 2 of the series is removed and the plate 16 inserted, after which the envelope 2, containing the plate 16 is positioned upon the bolt 7 and the nuts 8 are tightened. The bank is then 115 ready to receive deposits during the next period.

In Figures 5, 6 and 7 a modified form of container and supporting plate are shown. 120

This modification is intended for use during a period of a week. The envelope 2a is similar in structure to the envelope 2 of Figures 1 to 4, and may be of any suitable size and shape. The envelopes 2a are to be supported in a backing member similar to that used with the monthly form of container, and to that end are provided with slots 11a similar to the slots 11 of the envelope 2, which engage bolt 7 of the backing member 1. The envelopes 2a are provided in a series which is mounted upon the backing member in a manner similar to that shown in Figure 2.

On the front of each envelope is printed in radial form, a calendar for a certain week, the one shown in Figure 5 bearing the calendar for the week of January 4th, 1931. These calendars are so placed on the envelopes that a space is left below the calendar, which space receives and contains the coins deposited.

Associated with each unit of the calendar on each envelope 2a is an opening 13c of a size and shape to permit the passage of a coin into the envelope. These openings are in radial formation and closed by a backing sheet similar to sheet 14. The opening 13c may be modified as to shape and position or may be replaced by scored or perforated portions of the envelope similar to portions 15 in Figures 10 and 11.

A supporting plate 16a, bowed as shown in Figure 7 similarly to plate 16, is employed and has slots 20a to engage the bolts of the backing member 1. On the plate 16a are cut openings 17a of size and shape to permit the passage of coins and so arranged as to register with openings 13c of the envelopes 2a.

The manner of use of the weekly form of container is exactly the same as that of the monthly form, with the exception that each container is used during only one week and is then removed and replaced by the next of the series, being the one bearing the calendar for the next following week.

It will be seen that this invention provides a simple and inexpensive savings bank, which may be decorated in any desirable manner to make it highly attractive. It provides a means whereby coins deposited on different days are received in a common container; and means for indicating that a deposit has been made on or for a given day are carried by the containers.

The attractiveness and small cost of the bank, together with the opportunity for advertising which it affords, adapt it particularly to be supplied by banking institutions, both as an advertisement and as an incentive to saving by regular and frequent deposits of small amounts.

From the foregoing, it is thought that the construction, operation and many advantages of the herein described invention as defined by the claims will be apparent to those skilled in the art without further description, and

it will be understood that various changes in the size, shape, proportion and minor details of construction may be resorted to without departing from the spirit or sacrificing any of the advantages of the invention.

What I claim, is:

1. A calendar savings bank comprising a container of flexible material having a calendar upon one wall, said wall having openings associated with the units of the calendar and permitting the passage of coins through the wall, and a reinforcing plate removably located within the container and supporting the wall, and said plate having openings spaced to register with the openings in the wall and permitting the passage of coins through the wall and plate into the container.

2. A calendar savings bank comprising an envelope, a calendar printed upon the face of the envelope, perforations permitting the passage of coins into the envelope associated with the units of the calendar, a curved plate adapted to be inserted into the envelope to space the sides thereof, and openings in the plate spaced to underly the perforations in the envelope and permitting the passage of coins into the envelope.

3. A calendar savings bank comprising a backing member, a series of envelopes adapted to be supported thereon and removable singly, calendars printed on the faces of the envelopes, openings permitting the passage of coins associated with the units of the calendars, and a curved plate supported upon the backing member and adapted to be inserted into the envelope in use, and openings in the curved plate spaced to register with the openings of the envelope overlying the plate.

4. A calendar savings bank comprising a backing member, a flexible receptacle removably supported thereon having a calendar upon one wall thereof, weakened portions of the wall associated with the units of the calendar and adapted to be ruptured by pressing a coin against such portions, a curved metal plate removably positioned within the receptacle to support the printed face thereof, and openings in the plate spaced to register with the weakened portions of the receptacle and permitting the passage of a coin through the wall and plate into the receptacle.

5. A calendar savings bank comprising a backing member, a flexible container removably mounted thereon having a calendar upon one wall, said wall having openings associated with the units of the calendar, a thin backing sheet attached to the inside of the perforated face of the container adapted to be ruptured by the passage of a coin through the openings, and a metal plate removably positioned within the container to support the calendar-bearing wall thereof, and openings in the metal plate spaced to register with the openings of the receptacle and per-

mitting the passage of coins through the wall and plate into the receptacle.

6. A calendar savings bank comprising a backing member, and a series of coin receiving envelopes supported thereon and successively removable therefrom, a plate adapted to be detachably placed in the foremost envelope for supporting the front wall of the said envelope, and means on said front wall for permitting the passage of the coins and for indicating that coins have been deposited therein.

7. A calendar bank comprising a collapsible container having a calendar upon its outer exposed wall, said wall having openings associated with the units of the calendar to permit the insertion of coins, and a plate removably positioned within the container and adapted to space the walls thereof and to reinforce the calendar bearing wall.

In testimony whereof, I affix my signature.

NEAL D. HOWARD.
